ABSTRACT

Method and apparatus involving a continuous, chain-driven, palletized automatic storage and retrieval system. Storage of the vehicles is accomplished above or below ground level so that the ground or grade level is free to be used for receiving, loading and unloading, and discharging. For above ground installation the lower run of the conveyor has a dip-down section to the loading and unloading area at grade level and for the underground installation the system has a rise-up section. Pusher mechanisms in the receiving area engage the vehicle wheels and move it from the entrance of the parking system toward the loading and unloading area. A pallet is brought down or up and into loading position from the conveyor and a vehicle is automatically moved onto a loader-unloaded lateral transfer platform by a pusher mechanism. The loader then moves transversely to align the vehicle with the selected position on the pallet and pusher mechanisms on the loader automatically transfer the vehicle onto the pallet. When cars are to be retrieved the pallet is brought down or up into loading-unloading position and the vehicle is automatically pushed off the pallet onto the unload section of the transfer platform. Tire or wheel pusher mechanisms on the unloader part of the transfer platform push the vehicle into the parking discharge area where it is retrieved and driven away by the customer. The invention utilizes a "time in" system to identify vehicles and spaces for storage and retrieval.

METHOD AND APPARATUS FOR AUTOMATIC STORAGE AND RETRIEVAL OF AUTOMOBILES

BACKGROUND OF THE INVENTION

The invention relates generally to the art of vehicle and material storage and more particularly to an overhead or underground, continuous conveyor, palletized system for storing vehicles and other materials for automatic storage and retrieval.

With the increasing numbers of automobiles in urban areas in recent years, parking, particularly in large metropolitan centers, for relatively short periods of time has become an acute problem. As a result numerous types of parking systems, both drive-in and mechanical, for accommodating large numbers of cars have been developed. Some of these systems are partially automatic and utilize one or more elevators for raising the car to levels above street grade. When the car or vehicle has been raised to a particular level in the elevator it must be taken off the elevator and moved to a parking stall. In other systems the cars are driven on and off the elevators, and at other times they are automatically transferred on and off. In those mechanical systems in which cars are driven on or off or where the system is entirely drive-in and drive-out a substantial amount of space in the installation is devoted to open areas or aisles so that the cars can be moved around. In systems in which cars are transferred by elevators automatically moved into and out of a parking slot the problem is largely one of being able to store and retrieve the vehicles in peak traffic periods.

Many mechanical parking systems have been designed, the great number of which are impractical. As those skilled in the art are aware many structures have been conceived around a continuous conveyor concept. Again however the problem in any system is cost per car space and the handling of vehicles in peak traffic periods. If vehicles are left in a receiving area for the parking station attendants to store, the ability to absorb cars is limited by how fast an attendant can remove the vehicles from the receiving section and get them to stalls. In many parking installations therefore it is well-known that in peak traffic periods cars may line up in the street outside the entrance to the parking site awaiting their turn to enter. Thus, known mechanical parking systems cannot absorb vehicles as rapidly as they should in peak periods, nor can they retrieve and discharge quickly enough during rush hours such as in the late afternoon. However, with the increase in population and automobiles placing a great demand on land in metropolitan areas, it becomes increasingly essential that land available for parking be efficiently utilized. Many factors will determine the success or failure of parking systems, but it is recognized that mechanical parking because of its more efficient utilization of available space will certainly be looked to as one solution to solving metropolitan traffic congestion.

SUMMARY OF THE INVENTION

The invention is directed to a vehicle and materials handling method and apparatus which includes an open ground or street level area above or below which is disposed a continuous, palletized vehicle storage conveyor. The storage conveyor has a series of horizontally disposed trays or pallets driven by sprocketless chains. Each of the pallets will be driven by connection to a

chain at a central point on the sides of the pallet, while the four corners of the pallet will be supported by free running rollers engaging track structure comprising part of the conveyor system. Since the conveyor is raised or below ground there will be a dip-down or rise section from the lower or upper flight of the conveyor so that the pallets may be brought to a loading and discharge station at ground level. Associated with the pallet is a loading and unloading transfer platform. The pallets will accommodate several vehicles in a side-by-side relationship. The loader-unloader platform will receive a vehicle from an entrance lane and which vehicle is being automatically moved from the entrance towards the loader by a wheel engaging or pusher mechanism. When a vehicle is on the loader it will then be moved transversely into alignment with the desired parking position on the pallet. A wheel pusher mechanism on the loader then moves the vehicle onto the pallet. The pallet is then moved up away from the loading position and up or down into the conveyor so that the next loading or unloading may take place. The platform will raise and lower so that the tire pusher mechanisms thereon do not interfere with pallet movement and so that lateral movement is not impeded. Since the entrance lanes to the parking site will have to be separated for customer convenience there will normally be fewer receiving lanes than there are spaces on the pallets. Thus, transverse movement by the loading platform is needed. When a vehicle is to be discharged the pallet will be brought to the unloading position, the unloading platform will be brought into alignment with the vehicle to be discharged, the platform will be raised and its pusher mechanism will transfer the car off the pallet onto the unloader portion of the platform. The platform will then move into alignment with one of the discharge lanes and wheel pusher means will transfer the car off the platform and into the discharge lane. Stop mechanisms in the entrance lanes, on the loader portion of the platform, and in the discharge lanes will automatically hold a vehicle from any movement other than that desired. The various pusher mechanisms will be such that they are synchronized to take both the smallest and the largest wheel base automobiles. The trackage in the conveyor is such that the rollers are the corners of the pallet will help support the vehicle weight on the pallets and to maintain the pallets in their generally horizontal position. A monitoring system for vehicle identification utilizes the "time-in" figures on the customer's ticket and assigns a pallet space number to the time.

It is therefore among the many features, advantages and objects of this invention to provide a parking system apparatus and method which will permit the stacking of cars in a receiving or reservoir area while they are waiting to be loaded. The cars will be moved forward automatically after being left by the customer in a receiving lane. Hence, the accumulation of cars waiting in the street to enter the parking site is minimized. It is another feature to provide for completely automatic handling of the vehicle from the time it enters the site until it is driven away from the discharge area. It is another feature to provide a dip-down or rise up conveyor which brings the carrying pallets into position at entrance and discharge level. It is a further feature to utilize a platform for lateral move-

ment so that cars may enter the parking site in spacious receiving lanes and be moved closer together for actual storage. It is another feature to provide a large drive-in or receiving reservoir area so that in peak periods a great number of vehicles can be held in the receiving area beneath or above the parking conveyor. It is another feature to provide a system which can be adapted to almost any site regardless of length or width but in any case in which the number of storage lanes is greater than the number of receiving and discharge lanes. The system can be used as well for underground parking as for above-ground parking. Another feature is that this installation minimizes expensive equipment since gears and sprockets for the main conveyor chains have been eliminated. The conveyor sections can be modular thus making it easy to vary the length of a particular conveyor according to site requirements. The system will compete favorably on a cost-per-space basis with both drive-in and drive-out garage systems and other mechanical parking systems. This system eliminates expensive equipment required to position, push or pull the car out of a stationary parking stall and thus cuts down substantially on machinery and maintenance costs. The invention utilizes a unique loader-unloader platform operating in conjunction with the dip-down or rise-up positioning of the vehicle pallets. There is in this system no need to seek or locate cars for loader handling because they have already been aligned by the receiving lanes into a predetermined pick-up position. There are no mechanisms required for lifting or lowering the cars. Rather the cars are simply pushed and rolled into desired positions by simple wheel engaging means. The system contemplates loading and unloading on a common flat platform. Longitudinal car movement from receiving to loader and from loader to pallet is accomplished by a series of synchronized steps. The pushers are attached to a motor-driven chain and are extremely simple and low cost considering the functions they provide. When the loader is in position, one of its tire pushers will extend into the receiving area tire guide lane so that it may rapidly pull a car from the receiving area onto the loader platform. The unloader pusher will also extend beneath the discharge area so that it can rapidly push a car clear of the unloading area on the platform. To provide a conveyance means for cars on the pallet, a tire pusher mechanism will be attached to the loader platform area directly below the pallet. This tire pusher will engage the wheels of any automobile which is sitting on the pallet by simply passing through a slot in the pallet wheel channels. The system is designed for speed and arrestor mechanisms insure that the car will not roll off the pallets and traverse platform. The receiving and discharge areas are spacious, safe and oriented toward customer convenience. The monitoring system is uniquely simple in that the "time-in" figure on the customer's ticket identifies the car. A space number is also added to the time figure to accurately identify a given vehicle and its storage location.

BRIEF DESCRIPTION OF DRAWINGS

FIG. 1 is a schematic side elevation view showing the general configuration for the conveyor tracks and the location of the transfer platform with respect to a pallet in the load or unload position;

FIG. 2 is a plan view at ground or grade level showing receiving lanes, discharge lanes, transfer platform, and pallet to further illustrate the general view of FIG. 1.

FIG. 3 is a partial plan view showing further details of the receiving area, loader portion of the platform, and pallet with a vehicle in position in a receiving lane for loading;

FIG. 4 is a side elevational view of FIG. 3 further illustrating the sequence of steps for raising the platform into load position, transferring the car from the receiving lane onto the loader area of the platform, and then transferring the vehicle onto the pallet from the loader;

FIG. 5 is a partial plan view showing that the vehicle of FIG. 4 has been transferred onto the platform and the platform then moved laterally to position the vehicle in the center parking space on the pallet;

FIG. 6 is a further illustration of the detail of FIG. 4 showing the wheel stops in position for holding the vehicle against movement while on the pallet;

FIG. 7 is a partial side elevation view showing that the loader platform has been lowered and the pallet has begun to be moved upward into the conveyor with the vehicle;

FIG. 8 is a partial plan view showing the unloader portion of the platform with a vehicle which has been moved off the pallet onto the unloader portion and aligned with a discharge lane;

FIG. 9 further illustrates details of the tire pushing mechanism at the unloader end of the platform;

FIG. 10 is a partial side elevation view of the discharge end of the conveyor mechanism illustrating details of the track structure;

FIG. 11 is a partial side elevation view to be taken in conjunction with FIG. 10 for showing the remainder of the dip section and the details of the trackage whereby the pallets are raised back into the main storage part of the machine;

FIG. 12 is a partial prospective view of one side end of the conveyor system showing that the main chain rides in the center track end section to which a pallet is connected, and further shows how rollers are connected to the corners for riding in the inside and outside track end sections;

FIG. 13 is a typical cross-section view taken transversely through the machine to show details of construction of the trackage for carrying both the chain and corner support rollers;

FIG. 14 is a cross-sectional detail view of a pallet corner roller as it is supported on the track;

FIG. 15 is a cross-sectional view showing the details of a pallet and chain connection;

FIG. 16 is a partial side elevation view showing details of the main mechanism for driving the main conveyor chains;

FIG. 17 is a partial elevation view showing further details of the main drive mechanism of FIG. 16;

FIG. 18 is a plan view of a pallet showing details thereof including pusher slots and wheel stops for holding the car in position on the pallet;

FIG. 19 is a cross-sectional view of the pallet taken along the line 19-19 of FIG. 18;

FIG. 20 shows details of the wheel stop mechanisms on the pallet;

FIG. 21 is a plan view of the basic frame structure and drive components of the loader-unloader platform;

FIG. 22 is a partial side elevation view of the transfer platform of FIG. 21 further illustrating details of the platform lifting and lowering structure and traverse drive;

FIG. 23 is a partial side elevation view showing details of the tire pusher mechanism mounted on the center portion of the platform which is used in conjunction with a pallet;

FIG. 24 is a partial cross-sectional view of the device of FIG. 23 further illustrating details of the tire pusher mechanism to be used on the pallets;

FIG. 25 is a partial side elevation view of the tire pusher mechanism used in conjunction with loader-unloader sections of the platform;

FIG. 26 is a schematic perspective view showing the vehicle pusher and arrestor at the loading end of a receiving lane;

FIG. 27 is a perspective view of the receiving lane tire pusher showing additional details thereof;

FIG. 28 is a schematic diagram to assist in explaining the method of monitoring and identifying vehicles and storage spaces; and

FIG. 29 is a view showing underground installation of the invention.

DESCRIPTION OF PREFERRED EMBODIMENTS

FIGS. 1 and 2 show diagrammatically a typical above-ground parking installation employing the apparatus and method of this invention. While the building exterior or architecture in which the mechanical parking system is housed may vary considerably, it will be appreciated that the system has conveyor structure generally designated by the number 10, an entrance area generally designated by the number 12, a loader-unloader platform generally designated by the number 14, and a discharge area generally designated by the number 16. The conveyor itself has an upper flight of track end sections 20 and 22, and middle track or chain section 24, all of which are located at the discharge end of the conveyor structure. In like manner the entrance end of the parking site has inner and outer roller track end sections 26 and 28 and chain track end section 30. The dip portion has roller down tracks 32 and 34 and down chain track 36. On the up side the dip portion has roller up tracks 38 and 40 with chain up track 42. The structure will be provided with a series of pallets 44 connected to chains in each side of the track structure as will be more fully hereinafter described.

Transfer platform 14 will have a loader section 46 and unloader section 48 interconnected by framework extending under the pallet station and its details also will be more fully described hereinafter. Entrance area 12, for purposes of illustration, is shown to be at street level 50 and so is the discharge area 16. A pit 52 is sunk below grade level to accommodate the traversing platform 14 and its operating parts. The entrance or receiving area 12 has two incoming lanes with channels 54 and 56 into which the left wheels of the vehicle are driven. Once the left wheels are in channels 54 and 56 the customer may then leave the car and feeder pusher mechanisms for engaging the wheels of the car will move it as desired toward the loading area. Trays or pallets 44 are shown to be three cars wide and they also contain wheel channels 58, 60, and 62. The loader and unloader sections 46 and 48 of the traversing platform

14 have wheel channels 64 and 66 respectively. Finally, the discharge area 16 has wheel channels 68 and 70.

FIGS. 3-9 illustrate details of the method and cycling or sequencing steps with greater particularity. FIGS. 3 5 and 4 show the area at the end of the receiving zone, together with the loader part 46 of the traversing platform 14, and the entrance end of the pallet 44. It will be seen that vehicle C has proceeded along the receiving area wheel channel 56 and its motion has been arrested by stop 72. In order to load vehicle C onto a pallet 44 the stop 72 holds the vehicle until traverse platform 14 is in position. Platform 14 is moved so that its wheel channel 64 is brought into alignment with receiving wheel channel 56. Platform 14 is then raised and loader pushers 74 extend above the slot 82 in channel 56 to engage the left front tire. Pushers 74 are attached to chain 76 which in turn is mounted on sprockets 78 and 80 on the underside of loader section 46 so that they line up directly beneath said slot 82 extending into the receiving wheel channel. Raising and lowering of platform 14 permits the pallets to be moved into and out of their loading position. Thus, the only raise-lower movement of the platform is after a pallet is in position. In any event the platform does not raise a car but merely moves laterally with a car. In this regard the tire pushers at the end of a cycle step in such a position that no interference occurs when platform traverses in its up position. Stop 72 is retracted and pushers 74 when actuated are brought around sprocket 80 to engage the front wheel FW of vehicle C and pull it onto the loader section 46.

Once on the loader section 46 front wheel FW is arrested and held in position by stop 88. The traversing platform 14 is then laterally moved, without being lowered, to wheel channel 64 on the loader section 46 with one of the three storage wheel channels 58, 60 or 62 on pallet 44. When vehicle C has had its front wheel FW moved to the stop position on the loader section 46 40 the front wheel pusher 74 drops through an opening in channel 64. Continuing the sequence in FIGS. 5 and 6 it will be seen that loader section 46 has laterally moved into alignment with the center storage position of pallet 44, and vehicle C is ready to be moved onto tray 44. Referencing FIG. 4 again pushers 74 are actuated so that the rear wheel RW of the vehicle is engaged by a pusher 74 after the front pusher has dropped through an opening in the wheel channel and pushes the car off the loader. A pallet tire pusher 90 picks up the front wheel and completes the positioning by pulling the vehicle onto the pallet. Pallet tire pushers 90 are mounted on a continuous chain 92 extending around sprockets 94 and 96. When the front end of vehicle C has been pushed onto the pallet from loader section 46 a pallet tire pusher 90 as stated above picks up the front wheel FW of the vehicle and continues to move the vehicle into the position shown in FIG. 6. A front arrestor or stop 98 functions in cooperation with a rear wheel stop or arrestor 100 to hold vehicle C in storage position on pallet 44. Pushers 90 are mounted on the center section of traverse platform 14 and said pushers 90 extend upwardly into wheel channel slots 59, 61, or 63 on the pallet when platform 14 is raised. The pushers 90 are designed to stop in predetermined positions, that is with both below the pallet. This allows side movement of platform 14 in its up position regardless of whether the pallet is loading or unloading.

Vehicle C has now been brought onto pallet 44 and is in position. Platform 14 now is lowered so that the pallet is free to be moved from the loading and unloading station and up into the conveyor proper. Obviously the other two storage positions may be filled or emptied if desired before the pallet is moved. Each of the storage positions on pallet 44 has a right wheel supporting surface 102 which in turn has front stop 104 and rear stop 106 for engaging the right front wheel of vehicle C. Details of the stops and other particulars will be described more fully hereinafter. Once on the tray and wheel stops 98, 100, 104 and 106 are in position, platform 14 is lowered and the pallet moved up into the conveyor thus preparing the system for the next loading or unloading operation.

FIG. 7 is included to further illustrate what has just been described. Platform 14 has been lowered so that pallet pushers 90 are dropped free of the pallet leaving it in position to be moved side to side. The main conveyor chains are started and pallet 44 is moved in the direction shown by arrow 108. The dash dot line shows that pallet 44 has been moved from its loading and unloading position and is beginning its upward movement in the sloped uptrack sections 38, 40 and 42. Conversely if the vehicle had been moved off the pallet the empty pallet would be moving in the same way up into the conveyor for the next vehicle either to be stored or retrieved. It should be mentioned that the conveyor can move in either direction so that the least amount of time is required to move a given pallet to the load-unload station.

FIGS. 8 and 9 illustrate the sequence or cycling steps involved in unloading a vehicle from pallet 44. When the vehicle C to be retrieved is in position in the loading and unloading station on its pallet 44, traverse platform 14 is moved under the vehicle and raised. Pallet wheel pushers 90, as shown in FIG. 6, then engage the rear wheel of the vehicle and front stop 98 is retracted from the front wheel and pushers 90 then proceed to push 40 vehicle C onto unloader section 48 of platform 14. On the underside of and mounted on loader platform 48 are unloader pushers 120 secured to continuous chain 122 extending around sprockets 125 and 126 and the pushers 120 extend upwardly through slot 67 in wheel 45 channel 66. As pallet pushers 90 push the front end of the vehicle onto unloader section 48 unloader pushers 120 pick up the front wheel and continue to pull the vehicle onto the unloader platform. When the vehicle is free of pallet 44 as shown in FIGS. 8 and 9 the platform 14 is then moved into alignment with one of the discharge lanes in discharge section 16. With platform channel 66 in alignment with the discharge lane 70 the car is ready for unloading. It will be noted that unloader pusher assembly extends under the discharge areas 16 55 so that unloader pushers 120 can enter slots 69 and 71 in the discharge lanes 68 and 70. There are no pushers in the discharge wheel channels 68 and 70 except as slots 71 and 69 are provided to accommodate pushers 120. Pushers 120 enable the platform to move vehicle C completely off unloader section 48 and into the discharge zone 16 where the vehicle may be driven away.

CONVEYOR TRACK

FIGS. 10-15 are directed primarily to details of the conveyor track, main chains, main conveyor support

frame, and pallets. Much of the supporting framework for the conveyor tracks will not be described in detail since the description is not essential to an understanding of the invention and would unduly lengthen the specification. Suffice it to say that structural columns, cross-bracing and other supporting framework are engineered to support the loads which the conveyor will have to carry. In FIGS. 10 and 11 are shown outside roller track end section 20, center or chain track end section 24 and inner roller track end section 22. The dash-dot lines represent the working line or loci of the free roller axis and the chain roller axis. Thus when a pallet is moving along the upper flight 18 of the conveyor structure the axis of all rollers generally will follow the working line 130. As a pallet 44 comes to the end section moving in the direction of arrow 132 the leading corner rollers of the pallet will follow working line 134 to the outer roller track end section 20. In like manner the chain track end section 24 has working line 136 and the trailing corner rollers for the pallet will follow working line 138 around inner roller track end section 22. The working lines will converge again briefly into work line 140 on the lower run 25 until a pallet has advanced to the point where the work lines again separate and it begins to descend into the dip section. The trailing corner rollers follow work line 134 in roller track down section 32, the chain rollers follow work line 136 into chain track down section 36 30 and the leading corner rollers follow work line 138 into roller track down section 34. Again the work line will converge at the bottom into a common work line 142 until the pallet is loaded or unloaded or passes on through and begins its upward movement. For the lifting stage trailing corner rollers follow work line 134 in roller up section 38, the chain rollers follow work line 136 in chain track up section 42, and the leading corner rollers trace work line 138 in roller track up section 40. At the top of the dip area the work lines will once more converge into a common line 144 extending along the lower run of the conveyor structure.

It will be appreciated, reference being made again to FIG. 10, that as a pallet 44 approaches the end of the conveyor to drop down there will be a tendency of the pallet to tip or rock about its center connections with the chains. To counteract the tilting a self-leveling feature is provided by cantilevering the rear rollers to prevent front rollers from entering chain or front roller track. The leading roller must clear the gap between outer end section 20 and the chain track section 24. Accordingly, hold-down or restraining surfaces will be used on rollers at the trailing end of the pallet to insure that clearance of rollers at the leading end is made and that the rollers engage their proper track section before restraint is terminated. Thus the chain rollers will ride on track surface 150 but the lead corner rollers must clear gap 152 and engage roller track surface 154 extending around the outer track section 20. In like manner the trailing rollers must ride on track surface 156 so the forward roller track is long enough to hold the front end of the pallet up to insure that the rear roller will drop into section 22 on track 156. As will be appreciated pallet load distribution will be shifted from one surface to another in a given track so that a bearing surface 158 must be provided in outer track section 20 and a load bearing surface 160 provided with respect to

the chain track section 24 and a surface 162 provided for the inner roller in roller track section 22.

In the dip section the trailing rollers will have not only outer dip section 32 with track surface 163 but will be provided with coacting roller surface 164 for guidance of the rollers. In down section 36 having chain roller surface 165 for the chain additional track guidance will be provided in surface 166. Inner down track 34 will have load surface 167. On the upside of the dip section guide surface 166 for the chain rollers will continue to extend at least part way up the chain track section 42 which has track bearing surface 169. Roller track up section 40 will have load bearing surface 171 and a cooperating roller track surface 168. FIGS. 10 and 11 further show roller restraining surfaces 170 and 172 along the top run at the end of the conveyor as well as guide and restraining surfaces 174 and 176 shown in FIG. 11 at the top of the rise where the pallets reach the conveyor's lower run. In this regard reference is made to FIG. 13 showing a typical cross-sectional view transversely through the conveyor to further illustrate details of the track structure and to more clearly indicate how restraining or guide surfaces 170, 172, 174 and 176 are located. FIG. 12 has been included to illustrate prospectively how a typical end section on one side of the conveyor will appear. Again it is not seen to be important that all supporting frame components be pointed out.

The end track section at the entrance end of the conveyor are referenced again back to FIG. 1. There is provided inner roller track section 26, the chain or middle track section 30 and the outer roller track section 28. FIG. 12 will have to be read in conjunction with FIGS. 10 and 11 and 13-15 in order to fully appreciate the design. Thus track section 26 has roller surface 180 and a cooperating surface 182. The chain track section 30 has surfaces 184 and 186. Lastly roller track section 28 has surface 188 and cooperating track surface 190. Design and strength of the various track sections again will depend on which portion of the track at any given time is primarily responsible for load support. It will be seen that a roller link chain 192 with rollers 194 thereon is the prime drive means for the pallets. A restraining surface 196 is located above surface 188 for the outer track section to insure that both forward and rear rollers of the pallet move into their proper channels or tracks as the pallet comes to the end and begins to ascend and pass on to the top run 18 of the conveyor.

A pallet 44 is shown in dash dot line together with corner rollers 200 as illustrated in FIGS. 12 and 14. It will be seen that the guide track structure includes an inner wear strip 202 for each of the four corner rollers 200 connected to pallet 44 and an outer wear strip 204 on which the chain rollers 194 carry link chain 192. FIG. 14 illustrates one possible method of attaching the free running corner rollers 202 to the main frame structure of a pallet 44. In like manner FIG. 15 illustrates the manner in which the center connection of the pallet frame to the chain rollers 194 may be accomplished. Precise detail of the structural components is not critical to an understanding of the invention and hence identification of all parts of the rollers, frames and the like will be avoided except to note that corner rollers 200 are mounted on shaft 206 and chain connector rollers are mounted on shafts 208.

FIGS. 16 and 17 show the drive mechanism for the main chain 192. A motor and gear reducer 220 has output shafts mounting output pulleys or sprockets 22 which in turn drive sprockets or pulleys 224 through belt or chain 226. The pulleys or sprockets 224 are mounted on a shaft 228 which extends to each side of the conveyor. FIG. 17 shows one side only and it will be recognized that the opposite side is identical with the shafts extending to each side being of equal length so that torsional twist is the same for each side. Shaft 228 in turn drives a sprocket 230 which also drives a link belt 232. Portions of the chain 232 are shown in FIG. 16. On the chain 232 are adapters 234 which are spaced to engage the main chain rollers 194 for driving the main chain. It will also be noted that hold-down rollers 236 mounted above main chain 192 ride on the main links of chain 192 so that positive engagement of the adapters 234 can be made to drive the main chain.

PALLET DETAILS

FIGS. 18, 19 and 20 show further details of the pallets 44. The pallet is comprised of a frame including main side longitudinals 240 and 242 and end frame members 244 and 246 and in the instant embodiment is shown to have a three car storage capability. As described above each pallet has wheel channels 58, 60 and 62 with channel slots 59, 61 and 63 respectively and support pads 102 for the right wheels. The pallets will have additional framing structure but a description of all structural components is felt not to be necessary to an understanding of the invention. In FIG. 20 rear wheel stop 100 comprises side bars 250 extending down on each side of the wheel channel with a tire or wheel engaging connector 252 extending between side bars 250 and across the channel. The side bars are mounted on coaxially aligned shafts 254 and a spring 256 biases the rear stop in the up position as shown. A pin 258 restricts the spring-load movement of the stop so a car cannot roll back out of the stop once it is past the stop. As the vehicle rides onto pallet 44 the wheel pushes stop 100 down into the dotted line position shown and as soon as the wheel has rolled over and past the stop will snap back into the full line position indicated. In like manner stop 98 has side bars 260 which are pivoted at the lower end on coaxially aligned shafts 262. The side bars 260 are interconnected by the stop face member 264 extending across the wheel channel. Stop 98 is biased into its up position by link member 266 which pivots about shaft 268 and which is biased by spring 270 to ride under side bar 260 and force the stop into the position shown in full lines. A pin 272 limits the distance length member 266 may pivot. An actuator 271 on platform 14, has motor 273 and extender screw 275 and moves a pusher 269 into engagement with link 266 to pivot it into the dotted line position. This permits the stop 98 to drop away from the wheel and allows the vehicle to be moved. Another pin 274 prevents the side bars from flopping over on the pallet when the link member raises stop 98.

TRAVERSING PLATFORM

FIGS. 21 and 22 are directed to details of the loader-unloader traversing platform 14. In FIG. 21 the upper portion of the traverse platform has been broken away so that the support framework can be seen more clearly. A basic undercarriage generally designated by

the number 280 comprises longitudinal side frame numbers 282 and 284 and end cross frame members 286 and 288. Numerous other frame members and components are included but for simplicity of presentation the details thereof will not be set forth. The main undercarriage 280 runs on track wheels 290, two sets of which are under loader section 46 and one set of which is under the center section generally designated by the number 49. As can be seen the undercarriage is an elongated rectangular frame and its length is comparison to its width demands that adequate wheel support be provided and thus five separate track wheel support sections are provided. Wheels 290 are mounted on the underside of underframe 280 with conventional support structure and run on tracks 292. Obviously, and as those skilled in the art will appreciate, there will be spaced apart tandem wheel assemblies or trucks with wheels 290 for each of the five tracks 292. The tracks 292 as shown best in FIG. 22 are mounted on foundation blocks 294 and extend transversely across the width of pit 52. The undercarriage 280 is moved back and forth across the width of pit 52 on the tracks by a motor and reduction gear combination 296 located near center track 292. An output shaft 298 extends out both sides of the motor-reducer 296 and extends to chain sprockets 300 located at each end of the pit approximately between the two outer sets of tracks 292. The various journals and shaft bearing supports along the length of shafts 298 need not be described in detail. It will be noted that the motor-reducer combination 296 is located towards one side edge of pit 52. Near the other side edge of pit 52 are chain or link belt takeup sprockets 302 placed in line with the driven sprockets 300 on the other side of the pit. A link belt interconnects sprockets 300 and 302 with undercarriage 280 of the traverse platform 14. The carriage drive components are located so that traverse platform 14 moves sufficiently far in either direction to be able to line up with storage stations on the pallets and with the receiving and discharge lanes.

Undercarriage 280 provides the support, lifting and lowering means for traverse platform 14. As stated above the traverse platform has loader section 46 and unloader section 48 interconnected by a spanning frame or center section 49. The center section 49 extends under a pallet 44 and in addition to connecting loader and unloader sections 46 and 48 also supports the pallet tire pushers shown in FIG. 23 and more schematically described in FIG. 6. Raising and lowering is accomplished by a series of jack screw actuators 304 vertically disposed on undercarriage 280. As can be seen the jack screw actuators are located on the undercarriage generally directly above the tracks 292 and foundation blocks 294 under the unloader section 48 and under the loader section 46. Near the center of the undercarriage is motor 306 with gear reducer 308 and output shafts 310 from reducer 308. Shafts 310 drive right angle gear boxes 312 which in turn drive shafts 314 connected to each of the jack screw actuators. Thus the reversible motor 306 through the drive frame just described can power the screws up or down as desired. The tops of the jack screw actuators support loader-unloader sections 46 and 48. Note that four actuators 304 support each of the platforms 46 and 48.

WHEEL PUSHERS

FIGS. 23 and 24 are directed to details of the pallet tire pushers 90. Sprockets 94 and 96 around which the chain 92 extends are supported on the middle section 49 of traverse platform 14. A connector generally designated by the number 320, is a U-shaped member having depending side legs 322 and 324 and top piece 326. Legs 322 and 324 are provided with shafts to which are attached on the outside thereof guide and support rollers 328 and 330. The support rollers 328 and 330 roll in channel members 332 and 334. Means are provided between legs 332 and 334 to attach the top piece 326 of connector 320 to chain 92. On the upper surface of top piece 326 is mounted a pivotal pusher arm 336 which carries pushers 90. It will be noted that pushers 90 are supported in wheel channel 58, 60, 62 by support rollers 338 and 340 riding on wear plates 342 and 344. As pallet pusher 90 advances in the direction of arrow 346 it will reach an opening 101 not shown in this FIG. but which can be seen in FIG. 18. Since the wear plates 342 and 344 are no longer present to hold the pivotal pusher arm 336 and pushers 90 up in the channel the pusher arm and pusher will simply drop through the opening 101 and the chain 92 proceeds around sprocket 94. Arm 336 drops around its pivot connection and rides close to chain 92 as shown in FIG. 23. When a pusher reaches sprocket 96 traveling from the lower run of the chain to the upper run, guide means not shown engage support rollers 338 and 340 to guide the support rollers onto the wear plates 342 and 344 in the wheel channels so that the arm 336 and pushers take the portion shown on the top run. Openings 103 are provided in the wheel channels at the other end of the pallet from which the pusher mechanisms emerge as can be seen in FIG. 18.

FIG. 25 shows the type of pusher mechanism used for the loading and unloading operations. Reference in this instance should be made to FIGS. 4 and 9 for a more schematic presentation of the location of the load and unload pushers 74 and 120. These conveyors are attached to the underside of load section 46 and unload section 48 of the traverse platform 14. The connectors are similar to the pallet connectors shown in FIGS. 23 and 24 except that the arms 250 are rigid rather than pivoted. In order to maintain consistency numbers have been brought forward from FIGS. 4 and 9 to identify the basic component parts of the loader and unloader pusher structures.

FIG. 26 is a schematic perspective showing very generally the operation of the receiving lane pushers which bring a vehicle up to the ready-for-loading position shown by vehicle C in FIG. 4. Initially when vehicles enter a receiving lane (see FIG. 2) 54 or 56 the front left wheel FW is driven over the reception pusher generally designated by the number 352. The reception pusher has a ramp 354 at the back of a housing 356. In front of the housing is a rotatable cylindrical pusher roller 358 which engages wheel FW and rolls it along the length of either of the wheel channels 54 or 56. Since the reception pusher 352 is low the amount of rise up the ramp and across the top of the pusher housing and the crop to the front of pusher roller 358 is not great. The pusher assembly includes a block 260 which is connected to a horizontally disposed continuous

chain 362 which at the innermost end of the wheel channel extends around horizontally disposed sprocket 364. A motor 366 and gear box 368 provide the power for actuating chain 362 and the connector blocks 360 so as to move pushers 352. Stop 72 is positively actuated to remain in an up position and arrest movement of the vehicle by engaging the right front wheel of the vehicle as pusher 352 moves in a horizontal path around sprocket 364. Stop plate 72 has pivot arms 370 interconnected by pivot shaft 372. Shaft 372 in turn has sprocket 374 rigidly secured thereto driven by chain 376 which in turn is driven by reversible motor 377.

MONITORING AND SEQUENCING CONTROLS

FIG. 28 illustrates the monitoring and sequencing controls for the parking system. Cars enter receiving area 12 which for purposes of illustration is shown to be the right hand lane only. A swinging gate 380 may be used to block off one lane while cars are being taken into the other lane. As the car enters a receiving lane the vehicle operator stops at a ticket dispenser 382 and obtains his parking ticket. In this situation the cars are numbered 1, 2, 3 and 4 for the purpose of further illustrating the process of car and space identification. At 25 the time of entry and dispensing of a ticket for car number 4 the time of entry is 9:15.1 or nine o'clock, 15 minutes and 1 second. This time is printed on the ticket for car 4. Simultaneously with issuance of the ticket for car number 4 a signal is sent from the dispenser 382 to a control room printer through wire 384, to junction box 386, through line 388 to the printer-monitor unit generally designated by number 390. The printer-monitor unit includes a paper record 392 driven by roller 394 which is rotated by paper feed supply motor 396. As the signal comes in to the printer-monitor unit 390 the signal is relayed to an entry time slave printer 398 which prints the time 9:15.1 on record paper 392. A second motor 400 advances the paper record 392 for printing thereon of the pallet and pallet space identification by pallet space printer 402. Note to the left in FIG. 28 that car number 4 has its time of 9:15.1 printed on the record paper 392. Note also that a space designated 3 in the receiving lane is vacant on the 45 record since no car is in that space in the receiving lane. As will be seen car number 2 shows an entry of 9:11.6 and car number 1 which is first in line for loading entered at 9:11.7. Thus pallet space printer 402 receives a signal as illustrated by arrow 404 that car 50 number 1 is to be loaded. The pallet space on which car number 1 is to be loaded will be printed by printer 402 opposite the time car number 1 entered the receiving lane. After printer 402 has registered the particular pallet and indicated whether it is a center or left or right storage space the record then appears on paper 392 identifying a specific storage with a specific vehicle.

Tire stop 72 at the end of the receiving lane is released only when a car is to be loaded on a pallet and when stop 72 is released a signal is sent through the control room, through line 406 to motor 400 to advance the paper for the pallet space printer. In other words, a signal from the actuator for tire stop 72 will cause the paper record to advance one step each time a car is loaded. It will be seen that the automobile directly ahead of car number 1 entered at 9:09.3 and was loaded onto pallet number 12 in the center space.

When a customer returns for his car bearing a ticket entry of, for example, the earliest entry time of 9:03.3 the machine operator is able to consult the monitor paper record and find that this particular car is on pallet space 10R. The controls can then be actuated to deliver pallet 10 to the load-unload position so that the vehicle can be discharged and delivered to the customer.

ALTERNATIVE EMBODIMENT

FIG. 29 shows that the system may be modified for underground installation. As mentioned above the dip down section may be located on the upper run of the 15 machine to provide a "raise-up" section identical to the "dip-down" section shown in FIG. 1 for example. In this instance the loader-unloader platform would still be utilized to move the vehicles from receiving lanes to multiple car space storage pallets and from the pallets to the discharge area. It should be appreciated that much structural modifications would entail no departure from the inventive features of this method and system. The number of receiving and discharge lanes may vary according to the space available in a particular location as can the number of vehicle storage spaces provided on the pallets.

Referring further to FIG. 29 there is shown to be a continuous conveyor installation according to previously described specifications including tracks, sprocketless drive chains, and pallets. However no raise up section is shown to illustrate the use of movable elevator mechanism 410 which runs on tracks 412 and carries lift 414. Lift 414 has extension portion 416 which when the lift is aligned with the desired pallet may be extended to span the open space between lift and pallet. Pusher devices, not shown, enable the vehicle to be moved off the lift, across the extension portion and onto the pallets. While the elevator is shown to be movable it must be recognized that individual lifts could be provided for each parking width if desired.

What is claimed is:

1. A system for the storage and retrieval of vehicles comprising:
  - a. vehicle receiving and discharge areas generally at ground or street level to provide a collection and holding area for vehicles as well as a retrieval area, said receiving and discharge areas having generally therebetween a load-unload pallet station,
  - b. a continuous conveyor storage mechanism located in spaced relation above said receiving and discharge areas and including a plurality of generally horizontally disposed movable vehicle carrying pallets, said storage mechanism also having drive chains for moving said pallets and means for moving pallets to said load-unload pallet station,
  - c. a transversely movable loader-unloader platform in said pallet station which accepts a vehicle from said receiving area and moves the same onto a pallet and which moves a vehicle off said pallet into said discharge area, said platform being also movable vertically so that pallets can be moved into and out of said pallet station, and
  - d. vehicle pusher means for moving vehicles onto and off said platform and onto and off said pallets.

2. The system according to claim 1 and wherein said storage mechanism includes spaced apart track structure frames for supporting said pallet drive chains.

3. The system according to claim 1 and wherein said loader-unloader platform is provided with vehicle pusher means which assist in moving a vehicle from the receiving area, to the loader and to the pallet, to the unloader and to the discharge areas.

4. The system according to claim 1 and wherein vehicle stop and arrestor means are provided in said receiving area, on said platform in the loader-unloader sections thereof, and on said pallets.

5. The system according to claim 2 and wherein said pallets are connected generally intermediate their ends to said drive chains on each side and wherein the corners of said pallets are mounted on roller means which rollers are also supported on said track structure in said storage mechanism.

6. The system according to claim 3 and wherein said loader-unloader platform is an elongated structure extending under said load-unload pallet station having a loading section between said pallet station and said receiving area and an unloading section between said pallet station and said discharge area.

7. The system according to claim 6 and wherein said storage mechanism has a dip section therein for moving pallets down to said street or ground level to said load-unload pallet station and back up into said storage mechanism.

8. A system for the storage and retrieval of vehicles, comprising:

a. vehicle receiving and discharge areas generally at ground or street level to provide a collection and holding area for vehicles as well as a retrieval area, said receiving and discharge areas having generally therebetween a load-unload pallet station,

b. a storage mechanism situated above said receiving and discharge areas and including a plurality of generally horizontally disposed, movable, multiple vehicle, carrying pallets with support rollers mounted thereon, said storage mechanism also having a dip down section thereof which moves said pallets down to said ground or street level to said load-unload pallet station and back up into said storage mechanism, a continuous conveyor structure having spaced apart track structure frames including continuous drive chains therefor channels for said drive chains and including channels for said rollers,

c. a laterally movable loader-unloader platform in said load-unload pallet station which accepts a vehicle from said receiving area and moves the same onto a pallet and which moves a vehicle off said pallet into said discharge area, said platform also being movable up and down so that pallets can be moved into and out of said pallet station, and

d. vehicle pusher means for moving vehicles onto and off said platform and onto and off said pallets.

9. The system according to claim 8 and wherein said loader-unloader platform is provided with vehicle

pusher means which assist in moving a vehicle from the receiving area, to the loader, pallet, and to the unloader and discharge areas.

10. The system according to claim 8 and wherein vehicle stop and arrestor means are provided in said receiving area, on said platform in the loader-unloader sections thereof, and on said pallets.

11. The system according to claim 8 and wherein said pallets are connected intermediate their ends to said drive chains on each side and wherein the corners of said pallets are mounted on roller means which rollers are also supported on said roller channels of said track structure.

12. The system according to claim 9 and wherein said loader-unloader platform is an elongated structure extending under said load-unload pallet station having a loading section between said pallet station and said receiving area and an unloading section between said pallet station and said discharge area.

13. A loader-unloader mechanism for a parking system having a receiving area, discharge area, and storage area above said receiving and discharge areas, and including a vehicle load-unload pallet station between said receiving and discharge areas, comprising:

a. an elongated generally rectangular support, frame extending from said receiving to said discharge areas, and having means for lateral movement thereof,

b. a raisable and lowerable platform supported on said frame and having a loading section at one end thereof and an unloading section at the other end thereof and a spanning section interconnecting said loading and unloading sections and extending beneath said load-unload pallet station, and

c. vehicle pusher means in each of said loading, spanning, and unloading sections for moving vehicles from said receiving area to said loading section, from said loading section to said load-unload pallet station, from said load-unload pallet station to said unloading section, and from said unloading section to said discharge area.

14. The loader-unloader mechanism according to claim 13 and wherein said mechanism includes a first series of vehicle pusher means in said loading section which extend under a portion of said receiving area for moving vehicles onto said loading section of said platform.

15. The loader-unloader mechanism according to claim 14 and having a second series of vehicle pusher means in said spanning section for moving vehicles off said loading section of said platform into said load-unload pallet station and off said load-unload pallet station onto said unloading section of said platform.

16. The loader-unloader mechanism according to claim 15 having a third series of vehicle pusher means in said unloading section which extend under a portion of said discharge area for moving vehicles off said unloading section of said platform and into said discharge area.
